UNITED STATES PATENT OFFICE

LOUIS BROWNSTEIN, OF BROOKLYN, NEW YORK, ASSIGNOR, BY DIRECT AND MESNE ASSIGNMENTS, TO MONOPULSE TELETYPE CORPORATION, OF NEW YORK, N. Y., A CORPORATION OF NEW YORK

FUR POINTING MACHINE AND METHOD

Application filed April 9, 1930. Serial No. 442,825.

This invention relates to machines for advancing and setting individual hairs, and is particularly applicable to the setting of hairs in fur skins for the "pointing" of furs. It is to be understood, however, that my invention has numerous other applications and uses, and that I do not intend to limit myself to the particular use thereof specifically described hereinafter.

At the present time, there is a considerable demand in the trade for "pointed" furs. Such furs are made by setting light colored hairs in a fur skin. Each individual hair is handled by the operator manually and is at present set into the skin manually. This requires considerable time. The work must be done by skilled labor, and is therefore expensive.

My invention contemplates, among other things, the provision of means to which hairs may be supplied, for automatically setting the hairs in the skin and for advancing the skin in a predetermined manner so that line after line of the hairs are set therein at great speed, the entire process being completely automatic except for adjustment of the machine during operation to space the hairs as desired. My invention as applied to the "pointing" of furs requires only the supply of hairs in substantially parallel relation to a receptacle therefor, and the initial arrangement of the fur in place so that the hairs may be properly set therein. My invention further contemplates the provision of comparatively simple and efficient means for handling, manipulation and advancement of individual hairs, and of a method for "pointing" the fur.

The various objects of my invention will be clear from the description which follows, and from the drawings, in which,

Fig. 1 is a front elevation of my new machine.

Fig. 2 is a vertical longitudinal section thereof.

Fig. 3 is a vertical transverse section thereof.

Fig. 4 is a rear elevation, partly broken away, of my new machine.

Fig. 5 is a front view, partly in section, of the suction picker.

Fig. 6 is a bottom plan view of the same.

Fig. 7 is a bottom plan view of the end portion of the setting arm in the horizontal position thereof, showing particularly, the means for spreading the hair gripping and setting fingers thereof. 55

Fig. 8 is a vertical section, taken on the line 8—8 of Fig. 7.

Fig. 9 is a top plan view of the fur feeding mechanism of my machine, as it appears assembled on a fur feeding table. 60

Fig. 10 is a vertical section of the fur-holding roller, showing the setting fingers and presser foot in hair setting position.

Fig. 11 is a detailed elevation of the means for feeding the fur holding roller linearly 65 and for reversing the direction of feed.

Fig. 12 is an elevation of the means for adjusting the amount of the linear roller feed while the machine is in operation.

Fig. 13 is an enlarged elevation of the 70 means for intermittently rotating the fur roller.

Fig. 14 is a similar view of the means for maintaining the roller rotating gears normally out of engagement. 75

Fig. 15 is a similar view of the means for setting the roller linear feed gear in inoperative position, and

Fig. 16 is a perspective view of the hair gripping and advancing fingers and of the means for supporting and separating the fingers. 80

In that practical embodiment of my invention which I have illustrated by way of example, the frame 10 supports the various operating instrumentalities, said frame being in turn supported on a suitable table 11 (Fig. 9). The table 11 is provided with a cut away portion as 12 in which the fur feeding roll as 13 is supported as by means of the longitudinally movable and rotatable shaft 14. The roller 13 is given a predetermined linear intermittent movement on each complete cycle of operations, so that hairs may be set in the fur held by the roller, in the desired spaced relation and along a predetermined line. The roller is further given a transverse or rotary motion at the end of each line so as to bring another line of the fur into position for setting hairs in the fur while at the same time, 85 100

the direction of linear advance of the roller is reversed to set a new line of hairs in the opposite direction. The means for intermittently operating the roller for advancing the fur will be later described in detail.

Briefly, my new machine includes a hopper for receiving a supply of hairs in substantially parallel relation, together with devices for removing one or more hairs at a time from the hopper, for advancing the hair or hairs to the proper setting position on the fur, for gumming the hair during its advance to the setting position, for blowing upon the fur to head the hairs of the fur away from the setting position so as to allow the entrance between the displaced hairs of the hair to be set in the fur, and for intermittently advancing the fur as above indicated, to set line after line of hairs at the proper spacing to produce a "pointed" fox skin.

The hopper 15 (Figs. 1 and 2) is preferably provided with an opening at the top as at 16 and may taper near the lower end 17 thereof, terminating in an adjustable clamping wall as 18. Said wall may be provided with a suitable slot as 19, and is inserted into the groove 20 of a yieldable plunger rod as 21. The hopper is adjustably held in the groove 20 as by means of the set screw 22, passing through the slot 19. The hopper may thereby be adjusted so that the side openings 23 thereof are in the proper position to allow the entrance of the reciprocating suction picker 24 thereinto to withdraw hairs from the hopper.

It will be noted that the spring 25 is interposed between the upper end of the plunger rod 22 and the support 26 therefor, whereby undue pressure upon the hopper, exerted thereon by the suction picker, merely depresses the hopper against the action of the spring. The spring serves further to compensate automatically for the variation in the uppermost position of the exposed hair in the hopper as the height of the bundle of hair is lowered during the operation of the machine when the hair is being removed.

The upper surface of the bundle of hair is thereby maintained at the proper height to insure engagement thereof by the picker. The height of the hopper may be suitably adjusted as by means of the set screw 27 passing into the end 28 of the horizontal reciprocatory shaft 29 and tightened against the sleeve 26 for the hopper carrying rod 22. The shaft 29 is supported in suitable bearings in the frame 10 for reciprocatory movement forwardly and backwardly for the purpose of moving the hopper out of the way of the hair advancing mechanism at the proper time, as will be later described in more detail. The screw 27 engages the sleeve support 26 and clamps said support at the desired height whereby reciprocation of the

shaft 29 may reciprocate the hopper horizontally.

The means for reciprocating the shaft 29 will now be described.

Referring to Figs. 2 and 4, the cam shaft 30 is supported in suitable bearings in the frame 10, being illustrated as arranged horizontally and extending from the front to the rear of said frame and extending somewhat therebeyond.

A cam as 31 (Fig. 2) is secured to the shaft 30 near the rear end thereof and for rotation therewith, and engages the cam roller 32 carried by the end of the lever 33. Said lever is pivoted as at 34 on the bifurcated arm 35 secured to the rear wall 36 of the frame. The lower end 37 of the lever is inserted into a suitable slot 38 in the rear end of the shaft 29, whereby oscillation of that end of the lever carrying the cam roller 32 causes oscillation of the opposite end 37 in the slot 38, and thereby reciprocates the hopper shaft 29 and the hopper at the proper time.

The means for separating and removing the hair from the hopper 15 will now be described.

Said means includes a hollow rod 40 (Figs. 1 and 2) mounted for vertical reciprocation, and connected as by means of the flexible hose 41, to suitable means, not shown, as for example, a suction pump, for withdrawing air from the rod. The rod is in turn connected to the reciprocating operating rod 42 as by means of a suitable clamp 43. At its lower end, (see Fig. 5), the hollow rod 40 is suitably secured to the hollow suction block 44 of the suction picker 24, as at 45. The block is preferably of somewhat less width than that of the opening 23 in the hopper so that the block may enter said opening freely, the rod 40 communicating with the interior of the block. In its bottom wall 46, a series of closely spaced perforations as 47 is made, thereby providing openings through which air may be withdrawn to create a suction effect at the perforations 47 on the application of suction to the hose 41.

For adjusting the effective or operative areas of the perforations 47, I prefer to slidably secure the wedge-shaped adjusting slides 48 or wedges 48 on the bottom wall 46 as by means of the screws 49, passing through suitable enlarged openings as 50 in the block 44, and threaded to the wedges 48. Said wedges terminate preferably in comparatively sharp parallel edges 51 extending over and partly closing the perforations 47. It will be seen that on tightening the screws 49, the wedges 48 are maintained in the position in which they are set and in the desired relation to provide a groove as 52 therebetween through which suction through the rod 40 operates to draw a current of air into the exposed portion of the perforations 47. The hair withdrawn from the hopper is received and retained by

the suction in the groove 52 until removed therefrom. By loosening the screws 49, said screws may be moved to the left or to the right in the openings 50, sliding the wedges 48 with them and thereby enlarging or contracting the groove 52. By this means, I am able to adjust the effective widths of the apertures 47 and of the groove 52 so that one or more hairs may be removed from the hopper at a time, if desired, and so that adjustment is afforded to enable the suction picker to receive and withdraw hairs of different diameter, and so that the number of hairs removed at any one time may be accurately regulated.

15 Suction may be applied to the hose 41 continuously or intermittently, as desired, by means which are well known and hence which need not be shown nor described. As the suction picker 24 moves down, the hopper 15 moves rearwardly into vertical alignment therewith and into the proper position to allow the suction head to enter the opening 23. Further downward movement of the suction head causes said head to slightly compress 25 the hairs in the hopper, any undue pressure being taken up by the spring 25.

On the upward movement of the suction head, the suction through the perforations 47 and the groove 52 withdraws a single hair or 30 the desired number of hairs from the hopper into the position shown in Fig. 1, though it will be understood that the number of hairs so withdrawn is controlled by proper adjustment of the wedges 48.

35 Reciprocation of the suction picker operating rod 42 is effected by suitable connections to the shaft 30. As illustrated, (Figs. 3 and 2), said connections consist of the gear wheel 53 secured to the shaft 30 and meshing with the gear wheel 54 on the auxiliary shaft 55. The shaft 55 is suitably supported by the frame 10, being mounted in the block 56 depending from the top wall 57 of the frame, or any other suitable projection supported by the 40 frame. At the forward end of the shaft 55 is mounted the crank disc 58 and to said disc is pivoted one end of the crank 59 as at 61. The other end of the crank 59 is pivoted to the suction block operating rod 42 as at 60. It 45 will be seen that on rotation of the cam shaft 30, the shaft 55 is rotated through the gears 53 and 54, thereby rotating the crank disc 58 and operating the crank 59 to reciprocate the rod 42 and thereby, to reciprocate the suction picker 24 at the proper time to enter and leave the hopper.

50 The means for gripping the hair for withdrawing it from the suction head and for advancing and gumming the hair will now be described.

The turret 65, provided with preferably four or more or less similar arms as 66, is secured to the shaft 67, preferably in front of the frame 10.

55 The shaft 67 is mounted in a suitable bear-

ing in the front wall of the frame, and carries the gear wheel 68 arranged preferably inside of the frame and rearwardly of the front wall thereof. Interposed between the gear wheel 68 and the front wall of the frame is 70 the stop disc 69 provided with transverse grooves as 71 corresponding in number to the number of the turret arms 66. The spring-pressed pin 72 carries the roller 73. Said roller normally rests in one of the grooves 75 71, thereby preventing displacement of the disc 69, and preventing rotation of the shaft 67, and maintaining the turret 65 normally stationary. On rotation of the gear 68, however, the roller 73 leaves the groove 71 and 80 rides up on the circumference of the disc 69. At this time, the pin 72 is raised against the action of the spring 75, the pin being yieldably mounted in the sleeve 74 for this purpose and the spring being held in place 85 by a suitable cap 76 threaded into the top of the sleeve 74.

The gear wheel 68 is intermittently rotated as by means of the mutilated or segmental gear 77 mounted on the shaft 30 and meshing with the gear 68. It will be seen that on rotation of the cam shaft 30, the gear 68 is rotated through substantially a quarter turn, thereby rotating the turret 65, which is maintained in proper position at rest at its various stations by the roller 73, on the entrance of said roller into the groove 71 under the influence of the spring 75.

90 The hair gripping and advancing means consists of a series of pairs of spring-pressed cooperating members, one of which is mounted on the end of each of the turret arms 66, and the pairs of members being substantially identical, a description of one pair will suffice for all.

95 The pair of gripping and advancing fingers (Fig. 16) is designated generally by the numeral 80. I prefer to mount one of said fingers stationarily on an arm 66 of the turret 65. The stationary finger 81 may be secured to the arm 66 as by means of the screws 82 and is provided with an inner flat surface 83. The end portion 84 of the stationary finger 81 is made in the form of a hinge, being notched to receive the hinge portion 85 of the movable finger 86. A pin as 87 passes through the end 84 of one finger and the hinge part 85 of the other finger, whereby the movable finger 86 may swing about said pin as a pivot. Close contact between the fingers is assured by the provision of a cooperating flat surface 88 on the inner face of the movable finger. To urge said flat faces 83 and 88 toward each other so as to enable the hair to be gripped therebetween, a suitable spring as 89 is coiled about the pivot pin 87 and engages and presses upon the finger 86. Extending from the pin 87 and secured thereto, is the finger operating plate 90, preferably in the form of an arcuate segment. When 100

the pair of fingers 80 is at rest at the extreme left or at the extreme right, as shown in Fig. 1, to receive or forward the hair, the free end 91 of the plate 90 may be pressed forwardly, to rotate the pin 87 and to open the finger 86 relatively to the stationary finger 81.

In that position of the pair of fingers 80 illustrated at the extreme left of the turret in Fig. 1, wherein said pair is arranged to withdraw the hair from the suction block 24, the finger 81 is arranged in front of the hair while the finger 86 is arranged at the rear of the hair. The fingers are opened for that purpose by the plunger pin 92, which pushes the end 91 of the finger operating plate 90 forwardly, after the fingers 80 reach the hair gripping position and before the suction picker 24 has reached its uppermost or hair transferring position.

20 The plunger pin 92 is retracted under the influence of the spring 98 after the fingers 80 have been properly positioned on opposite sides of the hair and after the head 24 has delivered a hair therebetween, to close the fingers upon the hair under the influence of the spring 89. The hair is removed from the suction picker by the pair of fingers 80 on the rotation of the turret.

25 Since the plunger pin 92 is similar in construction to the plunger pins 93, 94 and 95, a description of one will suffice for all.

Said pins are each provided with a collar as 96 (Fig. 2) secured near the end thereof outside of the frame 10, for preventing the pin from being retracted too far toward the frame. Each of the pins is slidably supported by a suitable bushing 97 secured to the front wall of the frame 10. A spring as 98 abutting against the collar 99, serves to maintain the collar 96 normally in contact with the end of the bushing and maintains the pin normally in its retracted position out of contact with the plate 90.

30 The mechanism for operating the pin 92 comprises the cam 100 mounted on the shaft 30 and operating the cam lever 101, which is pivoted as at 102 to the bracket 103 (Fig. 3). At its lower end, the lever 101 is connected to the shaft 104 by suitable connections, such as the crank 105 and the link 106, whereby oscillation of the cam lever 101 causes similar oscillation of the shaft 104 at the proper time. A second crank 107 on the shaft 104 is connected by the link 108 to the plunger pin operating rod 109. Said rod is supported in a suitable bearing (not shown) extending from the frame 10, for vertical reciprocation and is bevelled at its upper end 110 for engagement with the inner end of the plunger rod 92.

35 It will be seen that on the rotation of the shaft 30 and the consequent oscillation of the shaft 104, the crank 107 raises the rod 109 through the link 108, whereby the plunger

rod 92 is moved outwardly by the bevelled end 110 into contact with the plate 90, at the proper time to open the fingers 80 and to position said fingers for the delivery of the hair therebetween by the suction picker. The rod 92 being then retracted by the spring 98 as the operating rod 109 is lowered, the fingers are closed about the hair.

40 As one form of the means for performing the gumming operation, I have utilized the segmental gear 77 which then engages the gear 88 and rotates the turret 65, thereby carrying the end of the hair through the gum box 112 and through the gum therein to gum the hair. The parts are so timed that just after suction picker 24 begins to rise, the shaft 29 is moved forwardly to carry the hopper 15 out of the way of the turret and out of the way of the fingers 80 thereon. Rotation of the turret brings the next pair of fingers 85 into position ready to be spread apart and ready to receive the hair from the suction picker 24 of the next upward reciprocation thereof.

45 After the hair has been transferred to and gripped by the next pair of fingers 80, the first pair carries the hair out of the gum box and into the position at the extreme right as viewed in Fig. 1, ready to transfer the hair to the hair setting mechanism. To effect the transfer, the fingers are opened at the proper time by the plunger rod 93 operating upon that plate 90 of the corresponding movable finger, as hereinbefore described in connection with the plunger rod 92.

50 The rod 93 is operated through the cam 113 which rocks the lever 114, pivoted at 102 and connected at its lower end to the link 115. Said link is secured to the crank 116 which is in turn mounted upon the shaft 117.

55 The second crank 118 projecting from the shaft 117 is connected to the plunger operating rod 119 as by means of the link 120. On rotation of the shaft 30, therefore, the lever 114 is oscillated, thereby oscillating the shaft 117, and therethrough and through the crank 118, the link 120 and rod 119, the plunger rod 93 is pushed forwardly due to the bevelled end 121 on said operating rod.

60 It will be understood that the mechanism just described for operating the plunger rod 93 is similar to that for operating the rod 92. However, the timing of said mechanism is slightly different as will be seen in connection with the description of the setting mechanism. The hair having been advanced into position for gripping by the setting mechanism and having been gummed, it is now in position to be gripped by the fingers of the setting mechanism and brought down on to the fur. Means for accomplishing these ends will now be described.

65 Said means in one form of embodiment thereof includes the block 125 (Fig. 1) preferably split as 126 and clamped by means of

the bolt 127 to the shaft 128. Said shaft is supported by suitable bearings in the front and rear walls of the frame 10, and is operated by the eccentric 129 (Figs. 2 and 5) mounted on the shaft 30, through the eccentric rod 130 and the crank 131. The block 125 is thereby oscillated at the proper time on the rotation of the shaft 30. As has been hereinbefore indicated, it is 10 desirable that the hair of the fur be parted at the point where the pointing or hair setting operation is to be performed on the fur, so that the fur hair does not interfere with the setting of the hair. For this purpose, I have 15 provided means for directing a stream of air upon the fur at the place where the hair is to set therein. A pipe as 132 is carried by the block 125 and is connected to the flexible hose 133 which is in turn connected to a suitable 20 source of air pressure (not shown) by means of the hose 134 through the intermediary of the valve 135. Said valve is operated by the cam 136 arranged on the shaft 30 at the proper time to direct a current of air 25 into the pipe 132, when the setting mechanism is in setting position.

For directing the air current or blast upon the fur in the proper direction to displace the hairs of the fur from the setting position, a 30 pair of pipes 137 and 138 are provided. One of said pipes 137 terminates on one side of the setting fingers 139, while the other pipe 138 terminates at the opposite side of said fingers, but the terminal ends of both of said pipes 35 are bent in a general downward direction so as to direct the current of air issuing therefrom upon the fur toward the point where the hair is to be set, to free said point of surrounding fur hairs. To support and operate the fingers 139, a rod 140 is rotatably supported at its lower end 141 in the block 125 and at its upper end, terminates in the internal cam block 142.

The cam block is provided with an internal 40 cam surface 143, engaging the rollers 144, which are secured to the ends 145 of each of the setting fingers 139. For pivotally supporting said fingers, a member 146 is provided, supported at the end of the rod 147, which is in turn secured to the block 125 at 45 one end and carries the spacing and supporting member 148 near its other end. The member 148 also carries the pipe 132 and rev- 50 olubly supports the rod 140.

In Fig. 7, I have shown spring-pressed pins 149 mounted on the member 146 and entering suitable recesses in the setting fingers 139 to urge said fingers into closed position. The fingers are normally pressed toward 55 each other into close contact by means of the springs 150. It will be seen that on the rotation of the rod 140 and the consequent rotation of the cam block 142, the cam surface 60 draws the finger ends 145 together against the action of the springs 150, thereby swing-

ing the fingers about their pivots 124 and opening said fingers. The opening of the fingers occurs twice; once when the block 125 is swung into its substantially vertical position shown approximately in Fig. 1 so that 70 the fingers 139 are positioned on opposite sides of the hair held at the extreme right of the turret by a pair of fingers 80, and again after the hair has been set.

It will be understood that the fingers 139 are opened sufficiently to compensate for any irregularities in the shape of the hair, such as those caused by bending, or the weight of the gum, or the like.

The rod 140 is rotated by means of the plunger rod 94 when the setting fingers near their upright position shown in dotted lines in Fig. 1. To operate the plunger rod 94, the cam 151 on the shaft 30 is provided. Said cam engages the lever 152 pivoted at 102 and terminating in the bevelled segment 153 (Fig. 3). The bevelled segment, in turn, engages the inner end of the plunger rod 94 and pushes said rod forwardly against the arcuate finger operating segment 154 which is secured to the rod 140, thereby rotating said rod and opening the fingers at the proper time, as has been heretofore explained.

It will be understood that the fingers 139 remain open for a comparatively long interval sufficient to allow the positioning thereof on opposite sides of a hair and until the shaft 128 comes to rest. The bevelled segment 153 is then withdrawn from the plunger rod 94, allowing the setting fingers to close about the hair, held by the advancing fingers 80, after which the plunger rod 93 is operated to open the advancing fingers 80. Thereafter, the shaft 128 is rotated in the opposite direction to carry the block 125 and the fingers and hose supported thereby down toward the setting position. Said setting position is indicated in Fig. 10. Just before the setting position is reached, the valve 135 is 100 opened, allowing a current of air to emerge 110 from the pipes 137 and 138, thereby blowing upon and displacing the hairs of the fur skin 160 to allow the gummed hair carried by the fingers 139 to be inserted into the space thus cleared among and near the roots of the displaced hairs.

As the gummed hair 161 reaches the setting position, the gum thereon causes it to 115 adhere to the adjacent hairs of the skin, whereupon the fingers 139 are opened by the plunger rod 95, acting upon the setting finger segment 154. The rod 95 is actuated by the cam 162 on the shaft 30, through the cam lever 163, which is pivoted at 102 and which terminates in a bevelled arcuate segment 164. The segment 164 engages the inner end of the plunger rod 95 and moves said rod forwardly after the setting fingers 139 have reached the setting position, to open said fingers and to maintain said fingers open while the block 125 130

125 is rotated back to the hair gripping position.

If desired, means may be provided for exerting pressure upon the hair after it has been set in the fur, though the gum on the hair is usually sufficient to hold it in place.

After the hair has been set into position by the setting fingers 139, and just before said fingers are opened, the presser rod 170 and its presser foot are operated to press upon the gummed portion of the hair, and serve to maintain the hair in place in the fur while the fingers 139 are opened and withdrawn. The presser rod 170 consists of a yieldably mounted section 171, terminating in a preferably curved presser foot 172, and normally held in its outermost position by means of the compression spring 173 inserted into the hollow end of the supporting rod 174 (Figs. 3 and 9). The supporting rod 174 is slidably mounted in suitable bearings 175 in the frame 10, and is provided with a rack 176 meshing with the segmental gear 177.

It will be seen that on the oscillation of the segmental gear 177 at the proper time, the presser rod 174 and therethrough, the rod 171 and the presser foot 172 are advanced into the setting position to firmly press upon the hair and set it permanently into place by pressure thereon, excess pressure being prevented by the yielding of the rod 171 against the action of the spring 173.

Similarly, as the presser rod 174 is withdrawn by the segmental gear 177, the spring 173 nevertheless maintains the presser foot in pressed contact with the hair, so that the gummed hair is acted upon for an appreciable period of time, the presser foot 172 being finally withdrawn near the end of the oscillatory stroke of the segmental gear. A pin 166 (Fig. 10) operating in the slot 165 of the rod 171 limits the movement of the rod 171 relatively to the rod 174 in either direction.

In order to oscillate the gear 177, it is mounted upon a suitable shaft 178 (Fig. 3). The shaft 178 carries the crank 179 connected by the crank rod 180 to the gear 181, so that rotation of said gear oscillates the segment 177. The gear 181 meshes with the gear 54 and is supported on the shaft 182 held in suitable bearings in the machine.

Power may be supplied to the machine from any suitable source to rotate the drive shaft 155. The worm 156 is mounted on the shaft 155 and meshes with the worm wheel 63 on the cam shaft 30. To operate the machine by hand, or to aid in halting it when desired, a hand wheel 157 is mounted on the shaft 158. Interengaging bevel gears 159 and 123 on the shafts 158 and 155 respectively, allow hand operation of the machine through the hand wheel and also allow braking action upon

the cam shaft when the hand of the operator is frictionally applied to the hand wheel.

Referring now to Figs. 9 to 15 inclusive, the means for intermittently advancing the roller 13 linearly and transversely so as to allow the setting fingers 139 to set a series of hairs along a predetermined line at the desired spaced intervals, and for rotating the roller 13 to set hairs along a different line when setting of the first line has been completed, will now be described.

Referring to Fig. 10, it will be seen that the roller 13 may be provided with a series of preferably radially outwardly extending pins 122 which are adapted to enter suitable holes as 183 in a preferably open end flexible belt as 184 preferably of canvas. Said belt is provided with a series of such holes or perforations 183, spaced apart about the same distance as the pins 122 and suitably reinforced, if desired, with eyelets. Rotation of the roller 13 causes the pins 122 to enter the holes or eyelets 183 in the belt 184 and thereby to advance the belt positively in a direction transversely of the fur. Said belt may be weighted at its lower ends as at 185 and 186 to maintain it in contact with the roller and with the pins 122. The fur 160 is arranged about the belt and may be removably secured thereto as by means of suitable clips 187, whereby rotation of the roller 13 insures the transverse advancement of the fur. Similarly, due to its connection with the belt 184, the skin is advanced linearly with the roller 13, so that different points along a predetermined line are brought in succession to the setting position to allow hairs to be set in the fur along the line.

The means for linearly advancing the roller 13 will now be described.

The shaft 14, carrying the roller, is of sufficient length to allow longitudinal movement thereof in the supports 200 therefor, as well as to allow rotation of said shaft within the supports, only one of which is shown. A similar shaft 214 is secured to the left end of the roller as viewed in Figs. 9 and 11 and is similarly of sufficient length to allow the roller to accommodate furs of maximum length and to move the fur from one end thereof to the other past the setting fingers. A support similar to the support 200 is provided on the table 11 for the shaft 214, so that the shafts 14, 214 and the roller 13 may move across the opening 12 in either direction intermittently.

To accomplish the intermittent movement of the roller, suitable brackets as 201 and 202 are secured to the shaft 14 and carry the spaced racks 203 and 204 provided with teeth 205 and 206, respectively. Said racks may be guided and supported by and between the rollers 198 and 199 carried by the post 200. The brackets 201 and 202 also carry the rod 207 on which the adjustable

stops 208 and 209 are mounted. Said stops are adapted to slide along the rod 207 and may be maintained in their adjusted position by means of the set screws 210 and 211 respectively. It will be understood that the stops 208 and 209 are set in the proper position along the rod 207 to determine the limits of the line along which the hairs are set in the fur. Toward that end, the stops are provided with reversing mechanism cooperating with the racks 203 and 204 to reverse the direction of linear movement of the roller 13 at the end of each line, as will be more fully described hereinafter.

15 The pinion 212 supported on the shaft 213, when meshing with the teeth 205, forwards the roller 13 in one direction and when meshing with the teeth 206, advances the roller in the opposite direction. Said pinion is therefore suitably mounted so that it may be held out of engagement with both racks or maintained in engagement with either one of the racks until the end of the line is reached, whereupon the pinion is moved into 25 engagement with the other rack to reverse the direction of linear movement of the roller. The shaft 213 is therefore supported at one end for rocking movement as by means of the universal joint 197. The extension 196 of said 30 shaft rests in the bearing 215 and carries the bevel gear 216. Near its other end, the shaft 213 is indented by means of a circumferential groove as 217, the groove being engaged by the spring-pressed ball 218 whereby the shaft 35 is so held that the pinion 212 thereon is maintained normally in its uppermost or in its lowermost position as the case may be, until moved therefrom.

40 A suitable spring (not shown) acts upon the ball 218 to cause it to exert pressure in the proper direction upon the shaft 213, said spring being enclosed in the sleeve 219 and being adjustable as to its force by movement of the screw plunger 220.

45 Means are also provided (Fig. 15) for maintaining the shaft 213, when desired, in such position that the pinion 212 is in its neutral or inoperative position. The roller 14 is in that case freed of its linear operating 50 means. The operator may then move the roller manually and linearly while the machine continues to insert hair in the fur. It will be seen, therefore, that when the pinion 212 is in its neutral or inoperative position, 55 the operator may shift the roller linearly toward the left or right, as he wishes, in order that hair may be set at the particular points in the fur which he selects, and this may be done while the machine is operating. Said 60 means comprises the notched lever 221 pivotally supported as at 222 to the post 223 and provided with the notch 224 intermediate of its ends. At its upper end, the lever 221 is provided with the spring 225 which is 65 adapted to snap about the projection 226 at

the upper end of the stop 227 to maintain the lever in place. Said stop may be held to the post 223 as by means of the screw 228. A suitable groove as 229 is provided in the post 223 for the reception of an intermediate portion of the shaft 213, which is movable substantially vertically in said groove.

70 As the lever 221 is moved toward its upright position, the edges of the notch 224 engage the shaft 213 and center said shaft between the sides of the groove, thereby moving the shaft into position wherein the pinion 212 is out of engagement with either of the racks. Toward the end of the movement of the lever 221, the spring 225 snaps about the projection 226 and maintains the lever in its upright position, whereby the shaft 213 is maintained in neutral position until moved therefrom.

75 Means are provided for intermittently rotating the shaft 213 on each complete rotation of the cam shaft 30 and thereby moving the roller 13 a predetermined distance for the setting of another hair at the proper distance from the hair previously set.

80 Said shaft 30 is provided with a crank disc 90 230 to which the crank rod 231 is pivotally secured at its upper end. At its lower end 232, the crank rod 231 is secured to the lever 233, which is slotted as at 234 to allow the fulcrum 235 therefor to be adjusted as may 95 be desired. The fulcrum 235 may consist of a suitable bolt 236, inserted through the slot 234 and through the slot 237 of the bracket 238, upstanding from the plate 239. It will 100 be understood that the plate 239 carries the roller feed mechanism and rests on the table 11. Said plate, however, may be adjusted relatively to the table for adjusting the feed mechanism to furs of different thicknesses 105 and is therefore provided with slots 240 and 241 for that purpose, being held to the table 11 by means of the bolts 242 and 243.

110 It will be understood, further, that a suitable collar or spacer as 244 may be interposed between the lever 233 and the bracket 238 for maintaining the parts in proper speed relation. Adjustment of the stroke of the end 245 of the lever 233 is obtained by moving the bolt 236 in the slots 234 and 237. It will 115 be seen from Fig. 12 that as the bolt is moved toward the left, as viewed in that figure, the operative movement of the lever end 235 is increased and the spacing between hairs correspondingly increased, and when the bolt 236 is moved toward the right and secured in position, the effective stroke of the lever end 120 245 is decreased and the hairs consequently set close together.

125 The lever 233, through a suitable one-way clutch 246 intermittently rotates the shaft 247 in one direction only. Said shaft carries the bevel gear 248, meshing with the bevel gear 216 on the pinion extension shaft 196 so that intermittent rotation of the shaft 247 is 130

transmitted to the pinion shaft and therefore to the pinion 212.

The clutch 246 may be of any suitable type effective to slip in one direction and to operate only in the other direction to turn the shaft. As shown, the clutch consists of a hollow cylinder 250 provided with an annular flange 251 engaged by a pair of dogs 252 which are suitably connected by a plate fitting inside of the cylinder 250 and are carried by the lever 233. Said dogs are suitably bevelled to grip the inner and outer surfaces of the flange 251 when rotation of the lever 233 occurs in the direction of the arrow of Fig. 12, and to slip over said flange without rotating the cylinder 250, when rotation occurs in the opposite direction. The cylinder 250 is provided with a hub secured to the shaft 247 and is engaged by the spring-pressed stop 253 for maintaining the cylinder stationary between the oscillatory movements of the dogs 252.

As the crank 231 oscillates the lever 232 about its fulcrum 236, the dogs 252 alternately grip and release the cylinder 250, thereby intermittently rotating the shaft 247 on each cycle of operations of the hair setting portion of the machine in one direction only, the stop 253 preventing backward rotation, whereby the pinion 212 is given the desired amount of rotation to forward the racks 203 and 204 in the desired direction, and through the shaft 14 to forward the roller 13 a predetermined amount to bring the next aligned point on the fur into setting position.

Means are provided for rocking the shaft 213 upwardly and downwardly about the joint 197 at the proper time to shift the pinion 212 from one of the racks to the other while the rotation of the shaft 213 continues in the same direction.

The longitudinal movement of the roller 13 is thereby reversed, as has been previously indicated. Said means comprises the fingers 254 and 255 preferably pivoted on the posts or supports 208 and 209 respectively, as at 256 and 257 respectively.

Suitable springs may be arranged on said pivots to maintain said fingers 254 and 255 normally in their uppermost and lowermost positions, respectively. As the shaft 14 moves towards the right (Fig. 11, the pinion 212 meshing with the rack 203 for that purpose), the under surface of the finger 254 engages the upper part of the shaft 213 and tends to depress said shaft under the influence of its spring. Further movement of the shaft 14 toward the right causes the finger 254 to exert sufficient pressure upon the shaft 213 under the influence of its spring to disengage the pinion 212 from the rack teeth 205 and to move the pinion downwardly into engagement with the rack teeth 206. Since the pinion continues to rotate in the same direction, the movement of the shaft 14 is

reversed by this means. Similarly, as the shaft 14 reaches the end of its stroke toward the left, (the pinion 212 at this time engaging the rack 204), the upper surface of the finger 255 engages the lower part of the shaft 212 and raises the pinion into engagement with the rack teeth 205, thereby again reversing the movement of the roller.

It will be understood that the posts 208 and 209 are set by the operator manually on the rod 207 at the proper points to cause the reversing operation just described to occur when the fingers 139 reach the extreme ends of the fur 160, or the end of the line on which hair is to be set and that for the setting of said posts, the neutral setting lever 221 may be operated to bring the pinion 212 into neutral position. When in such position, the shaft 14 and the roller 13 may be moved manually in a longitudinal direction to bring each of the ends of the fur temporarily into the setting position so that the posts may be set accordingly. When the pinion is free of the racks, the shaft 14 with the mechanism carried thereby may not only be moved longitudinally but may also be rotated by means of the hand wheel 260 at the extreme end of the shaft 14.

It will be further understood that the pinion 212 is normally maintained in either of its operative positions as the case may be, by means of the ball 217, which being arranged substantially midway between the racks 203 and 204, resists displacement of the shaft 213 upwardly or downwardly. Means are provided for imparting to the shaft 14, slight rotation in the proper direction to feed the fur 160 transversely to bring another line of said fur into setting position. The transverse or rotary movement of the fur is preferably accomplished at about the same time that the linear reversal of the roller 13 occurs, that is, when a new line is started.

The means for transversely feeding the fur will now be described.

Said means includes the shaft 261 rockingly supported in the bearing 262, and projecting through said bearing. One end of the shaft 261 is connected as by the universal joint 259 to the extension shaft 258 supported by the bearing 195. The shaft 261 (Fig. 14) is normally pressed downwardly as by means of the member 264 acted upon by the spring 265 to tilt the shaft in the bearing 262 and to maintain the free end of the shaft 261 normally in its lowermost position.

The spiral gear 266 at the other end of the shaft 261 is thereby normally maintained out of engagement with its cooperating spiral gear 267 mounted on the shaft 14. For allowing the gear 267 to rotate the shaft 14 at the proper intervals, while at the same time, preventing said gear from moving longitudinally with the shaft, a suitable feather and groove connection 268 is provided between

the gear 267 and the shaft 14. A tongue 269 projecting from the post 200 enters the groove 270 of the gear hub 271, and thereby prevents longitudinal movement of the spiral gear 267, the key of the feather and groove connection insuring rotation of the shaft 14 with the gear 267.

For imparting intermittent rotation to the shaft 261, a suitable gear as 272 is secured to the shaft extension 258, and meshes with the gear 273 on the extension 196 of the shaft 213. The intermittent rotation of the shaft 247 is thereby transmitted to the spiral gear shaft 261 whereby the speed of the spiral gear 266 is at all times in constant ratio to the speed of the pinion 212, and both are intermittently rotated during the operation of the machine.

In order to move the shaft 261 in the proper direction to mesh the spiral gears 266 and 267 together, suitable projecting fingers 274 and 275 are provided on the posts 208 and 209 respectively, the upper surfaces of said fingers being suitably bevelled to the proper height. As the shaft 14 nears the end of its stroke in either direction, the proper finger 274 or 275 passes underneath the spiral-gear-carrying end of the shaft 261 and engages the under part of said shaft. On the last part of the stroke of the shaft 14, and preferably at the time that the pinion 212 is shifted, the gear end of the shaft 261 is raised against the action of the spring 265, and the spiral gear 266 thereby raised to mesh with the gear 267 momentarily. The intermittent rotation of the gear 266 is now imparted to the gear 267, thereby turning the shaft 14 through the proper angle to advance the fur transversely through the required distance. At the same time, the pinion 212 being shifted, and the movement of the shaft 14 being reversed, the finger which has just raised the gear 266 leaves the shaft 261 which it has momentarily engaged so that the spring 265 becomes effective to depress the spiral gear end of the shaft 261, and to lower the spiral gear 266 out of engagement with the gear 267. Rotation of the shaft 14 is again accomplished at the other end of the longitudinal stroke of said shaft by the other finger.

For the purpose of adjusting the position of the fulcrum 235 during the operation of the machine, to advance the fur the required distance at each cycle of the hair setting operations and to thereby allow the setting of the hairs as closely as desired without halting the machine, a manually operated handle or lever 276 may be provided. Said lever is pivoted at its lower end 277 to the post 278 and is connected by the link 279 to the bolt 236 forming the lever fulcrum, whereby movement of the lever 276 the required distance shifts the fulcrum 235 and alters the stroke of the lever 233, and consequently changes

the distance through which the roller is fed after each hair setting cycle. The mechanism for feeding the hair transversely being connected operatively to the adjusting lever 276, it will be seen that adjustment of the transverse feed is simultaneously effected when the lever 276 is moved.

It will be seen that I have provided a simple and efficient machine and method for setting hairs and for pointing furs; that the operation of the machine is entirely automatic after the parts have once been set and that the machine can be operated at high speeds without attention other than the supply of material thereto and the change in the hair spacing by the operator when such change is desired and while the machine is running. It will further be seen that I have provided a machine and method well adapted to meet the severe requirements of practical use.

While I have shown and described certain specific features of my invention and a preferred embodiment thereof, it will be understood that I do not intend to limit myself thereto, but intend to claim my invention as broadly as may be permitted by the state of the prior art and the terms of the appended claims.

I claim:

1. In a machine of the character described, means for advancing hair toward setting position, means for directing a current of air on a fur skin at the setting position, and means for setting the hair among the natural hair of the skin.

2. In a machine of the character described, means for advancing hair, means for gumming the hair, means for blowing upon a fur skin to clear the hair of the skin away from the setting position, and means for setting the gummed hair in the cleared part of the skin and with the gum adhering to the natural hair of the skin.

3. In a machine of the character described, means for gumming hair, means for advancing the gummed hair into setting position, means for displacing the hair of a fur skin away from the setting position, and means for setting the gummed hair on the thus cleared portion of the skin and adjacent the roots of the displaced hairs.

4. In a machine of the character described, means for setting a line of hair among the natural hair on a fur skin, and means for advancing the skin into position to have another line of hair set thereon including a fur skin supporting roller and means for intermittently rotating the roller and for intermittently advancing the roller linearly.

5. In a machine of the character described, means for setting the gummed hair in adhesive engagement with the natural hair of a fur skin means for gumming the hair, means for linearly advancing the skin to bring

aligned points thereof into setting position, and means for transversely advancing the skin to bring another line thereof into setting position.

6. In a machine of the character described, a receptacle adapted to receive a plurality of individual hairs in substantially parallel relation, suction means for withdrawing hair from said receptacle, means for removing the hair from the withdrawing means and for advancing the hair, means for gumming the hair during the advance thereof, means for transferring the gummed hair from the advancing means into setting position, blower means for displacing the hair on a fur skin from the setting position as the gummed hair approaches said position, means for linearly advancing the skin, and means for advancing the skin transversely of the direction of linear advance.

7. In a machine of the character described, suction means for withdrawing hair from a hair receptacle, means for advancing the hair into setting position, means for gumming the hair during its advance, means for displacing the hair of a fur skin from the setting position, means for inserting the gummed hair among the roots of the displaced hair, and means for intermittently advancing the skin.

8. In a machine of the character described, means for intermittently advancing hair to be set toward setting position in a fur skin, means for gumming the hair during its advance, means for setting the hair on the skin, and means for intermittently advancing the skin between the setting operations of said setting means.

9. A suction member for withdrawing hair from a receptacle comprising a hollow block having a perforated bottom wall, and means for adjusting the effective width of the perforation in said bottom wall.

10. In a machine of the character described, a pair of relatively pivoted members having adjacent flat surfaces, a spring normally pressing the surfaces into contact, means for alternately spreading and releasing said members in hair gripping position to permit the spring to close the members on opposite sides of hair to be gripped, and means including a rotatable shaft for rotating the members about an axis spaced therefrom after said members have been closed, to advance the hair.

11. In a machine of the character described, a pair of spring-pressed gripping fingers adapted to be arranged on opposite sides of hair to be gripped, and means for alternately opening and closing said fingers to grip the hair comprising a pivot for at least one of said fingers, an extension on the finger projecting beyond the pivot, and a cam engaging the extension and adapted to

rotate the pivoted finger about the pivot in a given direction.

12. In a machine of the character described, a plurality of pairs of hair gripping fingers, means for operating said fingers to grip and to advance hair, means for gumming the hair, means for withdrawing the gummed hair from one pair of said fingers while another pair is receiving hair and for advancing the hair into setting position, means for blowing upon the hair of a fur skin to displace the hair of said skin from the setting position as the gummed hair reaches said position, means to set the hair among the roots of the displaced hair of the skin to adhesively secure the gummed hair to said roots and means for intermittently advancing the skin between setting operations.

13. In a machine for inserting hair in a fur skin, a pair of pipes bent so that the intersection of the prolongation of the ends of said pipes is arranged at a predetermined point, means for forcing air through said pipes to part the natural hair of a fur skin, and means for inserting hair among the parted hair of the skin.

14. In a machine of the character described, means for inserting hair in a fur skin, an outwardly convex presser foot for pressing upon a set hair, the inserted hair and a yieldable support for the presser foot.

15. In a machine of the character described, a pair of hinged fingers, means for advancing hair into a position between said fingers, a cam plate operatively connected to the hinge of the fingers and adapted to open the fingers as the hair is advanced to said position, and a spring adapted normally to maintain the fingers in closed position.

16. In a machine of the character described, a roller adapted to support a fur skin, means for linearly advancing the roller intermittently, means for inserting hair among the natural hair of the skin while the roller is at rest, and means for automatically reversing the direction of advance of the roller after a predetermined advance thereof.

17. The method of pointing furs comprising gumming the end of hair to be set in the fur, blowing upon the fur at the point where the hair is to be set to displace the surrounding hair of the fur, setting the gummed hair in place, advancing the fur linearly step by step in one direction while repeating the hair setting operations until a line of hair has been set across the fur, then advancing the fur transversely and setting a new line of hair during the intermittent linear advance of the fur in the opposite direction.

18. The method of pointing furs comprising arranging a plurality of hairs in a pile in substantially parallel relation, removing hair from the pile, gumming the hair, blowing upon the fur at the point at which the gummed hair is to be set while retaining

control of the hair, setting the hair into position among the hair of the fur, and advancing the fur linearly step by step until a line of hair has been set therein, and then advancing the fur transversely to start a new line.

19. In a fur pointing machine, means for supporting a fur skin, a hair container spaced from said means and adapted to hold a pile of straight hair in substantially parallel relation to each other, means for engaging and removing hair from the receptacle and means for delivering the hair so removed to the fur skin on the supporting means while maintaining the hair straight.

20. In a fur pointing machine, means for supporting a fur skin, a hopper spaced from said means and adapted to hold a loose pile of straight hair with which the skin is to be pointed, suction means for removing hair from said hopper, and means cooperating with the hair removing means for advancing the hair toward the skin.

21. In a machine for pointing a fur skin, a receptacle for a pile of straight hair with which the skin is to be pointed, and means for withdrawing hair from the receptacle in a direction transverse of the length of the hair and for advancing the hair to the skin.

22. In a machine for pointing a fur skin with hair, a hair receptacle, means for withdrawing hair bodily in a direction transverse of the length of the hair from the receptacle, and grippers adapted to receive the hair from the withdrawing means and to advance the hair toward the skin.

23. In a machine of the character described, means for gripping substantially straight hair, means for withdrawing the hair from the gripping means and for advancing the hair while maintaining the hair straight, means for gumming the hair during its advance, and means for setting the hair on a fur skin.

24. In a machine of the character described, means for advancing hair while maintaining the hair substantially straight along the length thereof including a pair of gripping fingers adapted to close upon the hair intermediate of the ends of the hair, and means for setting the hair on a fur skin.

25. In a machine of the character described, means for advancing straight hair including cooperating members adapted to grip the hair between its ends, and means for setting the hair on a fur skin.

26. In a machine of the character described, a hair receptacle, suction means for withdrawing hair from said receptacle, and means for moving the suction means toward and from the receptacle to control the advance of the hair.

27. In a fur pointing machine, a suction member having a groove in a wall thereof adapted to be substantially closed by hair on

the application of suction through said member and through said groove to hair arranged adjacent said groove, a pair of cooperating gripping fingers, a cam adapted to position said fingers on opposite sides, respectively, of hair to be gripped therebetween while the hair is retained by the member under suction, and a spring operatively connected to and arranged to close said fingers.

28. In a fur pointing machine, a pair of separable, normally closed, spring-pressed fingers, a cam adapted to open the fingers against the spring pressure and to release the fingers to close upon the hair, means for moving said fingers toward and from a fur skin to carry the hair gripped thereby into setting position on said skin, and means for intermittently advancing the skin during the return movement of said fingers toward the initial position thereof.

29. A fur pointing machine comprising means for handling at least one individual hair at a time, and means for inserting the hair among the roots of the natural hair of a fur pelt.

30. A fur pointing machine comprising means for gumming at least one individual hair at a time, and means for inserting the gummed hair among the roots of the natural hair of a fur pelt to be retained thereby.

31. A fur pointing machine comprising means for removing at least one individual hair at a time from a loose bundle of such hair, and independently movable means for inserting the hair in a fur pelt.

32. A fur pointing machine comprising means for removing at least one individual hair at a time from a loose bundle of such hair, independently movable means for inserting the hair in a fur pelt, and means for moving the pelt.

33. A fur pointing machine comprising means for handling at least one individual hair at a time, means for inserting the hair among the roots of the natural hair of a fur pelt, and means for moving the pelt to cause hair to be inserted by the inserting means at spaced intervals in the pelt.

34. A fur pointing machine comprising means for gumming at least one individual hair at a time, means for inserting the gummed hair among the roots of the natural hair of a fur pelt to be retained thereby, and means for moving the pelt to cause hair to be inserted by the inserting means at spaced intervals in the pelt.

35. A fur pointing machine comprising means for inserting individual hairs at spaced intervals among the roots of the natural hair of a fur pelt, and means adjustable by an operator during operation of the machine for moving the pelt to vary the spacing of the hair inserted into the pelt.

36. A fur pointing machine comprising means for handling at least one individual

hair at a time, means for inserting the hair among the roots of the natural hair of a fur pelt, and means adjustable by an operator during operation of the machine for moving the pelt to vary the spacing of the hair inserted into the pelt.

37. A fur pointing machine comprising means for gumming at least one individual hair at a time, means for inserting the gummed hair among the roots of the natural hair of a fur pelt to be retained thereby, and means adjustable by an operator during operation of the machine for moving the pelt to vary the spacing of the hair inserted into the pelt.

38. A fur pointing machine comprising means for removing at least one individual hair at a time from a loose bundle of such hair, independently movable means for inserting the hair in a fur pelt, and means adjustable by an operator during operation of the machine for moving the pelt to vary the spacing of the hair inserted into the pelt.

39. In a fur pointing machine, means for inserting hair into a fur pelt, means for supporting the pelt, means for advancing the supporting means linearly of said means, and means for rendering and maintaining said advancing means inoperative whereby the supporting means is rendered manually operable.

40. In a fur pointing machine, means for inserting hair among the natural hair of a fur pelt, means for advancing the pelt, and means for rendering the advancing means inoperative to permit the manual advance of the pelt.

41. In a fur pointing machine, means for gumming hair and for inserting the gummed hair into a fur pelt, means for advancing the pelt to space the hair inserted therein, and means for rendering the advancing means manually controllable.

42. In a machine for pointing fur, means for supporting a fur skin, means for parting the hair at a predetermined point on said skin to expose the roots of the natural hair of the skin at said point, a container for a loose bundle of straight hair, means for removing at least one hair at a time from the container, for gumming the hair, for advancing the hair, and for setting the gummed end of the hair among said roots, means for moving said supporting means transversely of the skin, and means for controlling the amount of the transverse movement while the machine is in operation.

43. In a machine for pointing fur, means for advancing and gumming the end of at least one individual hair at a time, means for supporting a fur skin, means for blowing upon the skin at a predetermined point to part the natural hairs thereof, means for setting the gummed end of the hair among the roots of the parted hair on the skin, means

for intermittently advancing the supporting means in a given direction to space the hair set in the skin, and means for varying the spacing of the hair set in the skin during the operation of the machine.

44. A machine for pointing fur including means for removing at least one hair at a time from a loose pile of such hair for gumming the end of the hair so removed and for advancing the hair toward the setting position on the skin, means for parting the natural hair of the skin at the setting position to permit the entrance therebetween of the gummed end of the hair to be set therebetween by the advancing means, means for intermittently advancing the skin in one direction, means for adjusting the distance of said intermittent advance while the machine is in operation, and means for advancing the skin in a direction at right angles to the direction of the first advance of the skin when the limit of the first intermittent advance has been reached.

45. A machine for pointing fur by setting individual hairs at spaced points among the roots of the natural hair of the fur skin including means for gumming the hair to be set in the skin, means for blowing upon the skin to part the natural hair thereof at a predetermined point, means for setting the gummed end of the gummed hair between the parted hair of the skin, and means for moving the supporting means.

46. A machine for setting straight individual hairs among the roots of the natural hair of a fur skin, including means for removing at least one individual hair at a time from a bundle of such hair, means for gumming the hair, means for supporting a fur skin, means for parting the hair of the fur skin to expose the roots thereof at a predetermined point, and means for advancing the gummed hair and for setting the gummed end thereof between said roots while the natural hair of the skin is parted.

47. A machine for setting straight individual hairs among the roots of the natural hair of a fur skin, including means for removing at least one individual hair at a time from a bundle of such hair, means for gumming the extreme ends of the individual hairs so removed, means for supporting a fur skin, and means for gripping the hair beyond the gummed ends thereof and for carrying said gummed ends in between the roots of the natural hair of the skin.

48. In a machine for handling hair, means for gripping and advancing at least one individual straight hair at a time, means for gumming the extreme end of the gripped hair, and means for removing the gummed hair from the gripping means and for further advancing the gummed hair to a predetermined point and into a predetermined position.

49. In a machine for handling hair, a suction member having a suction opening therein adapted to receive at least one individual hair on the application of suction to said member, means for reciprocating said member toward and from a bundle of straight hair to remove a predetermined number of individual hairs from the bundle by suction through said opening, and means for removing the hair from the suction member and for advancing the hair to a predetermined point. 10
50. In a machine for handling straight pre-cut hair, means for gripping at least one individual hair and for advancing the gripped hair, means for gumming the extreme end of a gripped hair, and means for effecting the transfer of the hair to a predetermined point with the gummed end of the hair free of said last-mentioned transferring means. 15
51. In a machine for handling hair, a hopper adapted to maintain a pile of straight hair in position to be removed therefrom, means for engaging at least one individual hair at a time intermediate the ends of the hair and for removing the hair from the hopper while maintaining the hair straight, and means for adjusting the position of the hopper relatively to the hair removing means to cause said removing means to engage the hair at 20 different relative sections of the length of the hair. 25
52. In a machine for handling hair, bodily movable means for gripping at least one individual hair intermediate the ends thereof and for advancing the hair so gripped toward a predetermined point, and means for removing the hair from the gripping means and for advancing the hair toward a second predetermined point in spaced relation to said first-mentioned predetermined point, both ends of the hair being maintained free of restraint during the advance thereof by said means. 30
53. In a machine for handling hair, means for removing a predetermined number of individual hairs from a loose bundle of such hair, and means for adjusting said removing means to change said predetermined number. 35
54. In a machine for handling straight hair, a container for a pile of loose straight hair, reciprocating means for determining the number of individual hairs to be removed from the container, and for engaging and removing the predetermined number of individual hairs from the container, and means for advancing the individual hairs so removed as a unit. 40
55. In a machine for pointing a fur skin including mechanism for handling hair and for determining the number of individual hairs handled thereby, means for removing the hair from said mechanism and for advancing the hair, means for gumming the hair, and means for setting the gummed hair in between the roots of the hair of the skin. 45
56. A machine for pointing a fur skin by a hopper of predetermined length, closed at 50
- setting hairs at spaced points among the natural hair of the skin, including mechanism for removing at one time from a loose bundle of hair, a number of hairs to be set in the skin, means for controlling the number so removed, 70 and means, movable in a path independent of that of said mechanism, for receiving the removed hair from the mechanism, for advancing the hair, and for setting the ends of the hair in between the roots of the hair of the skin. 75
57. In a fur pointing machine, a fur skin supporting roller, means for blowing upon the skin to part the hair thereof, means for setting hair upon the skin among the parted hair thereof, means for advancing the roller intermittently in a direction transversely of the skin, means for adjusting the amount of the intermittent transverse movement of the roller, means for adjusting the limits of the transverse movements of the roller, and means for rotating the roller at each end of the transverse movement thereof. 80
58. In a fur pointing machine, means for advancing, gumming and setting hair on a fur skin, a roller adapted to advance the skin, means for blowing upon the skin while the hair is being set therein, means for advancing the roller transversely of the skin intermittently in the interval between the setting of hair thereon, and means for adjusting the amount of the intermittent transverse movement of the roller. 85
59. In a fur pointing machine, an intermittently revoluble turret, a plurality of pairs of spring-pressed gripping fingers on said turret, a gum box adjacent the path of said fingers, a reciprocating suction picker having the limit of its movement in one direction adjacent one set of said fingers when the turret is at rest, and a pair of movable setting fingers adapted to be positioned adjacent the opposite pair of gripping fingers when the turret is at rest. 90
60. In a fur pointing machine, an intermittently revoluble turret, a plurality of pairs of spring-pressed gripping fingers on said turret, a gum box adjacent the path of said fingers, a reciprocating suction picker having the limit of its movement in one direction adjacent one set of said fingers when the turret is at rest, and a pair of movable setting fingers adapted to be positioned adjacent the opposite pair of gripping fingers when the turret is at rest. 95
61. In a fur pointing machine, an intermittently revoluble turret, a plurality of pairs of spring-pressed gripping fingers on said turret, a gum box adjacent the path of said fingers, and a reciprocating suction picker having the limit of its movement in one direction adjacent one set of said fingers when the turret is at rest. 100
62. A fur pointing machine including a hopper of predetermined length, closed at 105
- 110
- 115
- 120
- 125
- 130

- the bottom and open at the top, and adapted to receive parallel hair of substantially the length of said hopper, a support adapted to maintain said hopper removably in position, and a suction picker adapted to move into and out of the hopper.
63. In a fur pointing machine, a turret having spaced arms thereon, means for intermittently rotating said turret, a pair of fingers on each of said arms, one of said fingers being stationary, a shaft passing through one of the fingers, a lug on the other finger pivoted on said shaft, a spring on the shaft adapted to urge the movable finger into closed position, a cam extension at the other end of said shaft, and means for oscillating said extension to rotate the shaft and to open and close the fingers alternately to grip and to release hair arranged between the fingers.
64. In a fur pointing machine, a revolvable turret, a plurality of pairs of spaced gripping fingers on said turret, means for intermittently rotating the turret through an angle subtended by adjacent pairs of gripping fingers, means for opening and closing said fingers about a hair, a pair of setting fingers, means for opening said setting fingers to position the setting fingers about a hair held by one pair of gripping fingers while the turret is stationary, means for closing said setting fingers upon the hair substantially simultaneously with the opening of the gripping fingers, a pivot for the setting fingers, and means for rotating the setting fingers about the pivot to carry hair gripped by the setting fingers to setting position.
65. In a fur pointing machine, a fur skin advancing roller, means for intermittently sliding the roller, movable stops adapted to adjust the limits of the sliding stroke of the roller in either direction, means for rotating the roller through a predetermined angle at each end of the stroke, a blower adapted to part the hair of the skin for the reception of hair to be set thereon, means for advancing and gumming straight hair removed by said means from a pile of such hair, to the setting position, a blower, and means for setting the gummed hair at the setting position into engagement with the natural hair of the skin, while the natural hair has been displaced by the blower from the path of the hair to be set.
66. A receptacle adapted to retain straight hair in parallel relation, a reciprocating suction member movable into and out of the receptacle, and when moved out of the receptacle, being adapted to engage and carry hair therewith to remove hair from the receptacle, openable and closable gripping fingers, means for closing the gripping fingers upon the hair held by the suction member, means for rotating the closed fingers to remove the hair from the suction member, setting fingers adapted to remove the hair from the gripping fingers, means for oscillating the setting fingers to deposit the hair at the setting position on a fur skin, and a blower adapted to part the hair of the fur skin away from the setting position to clear the skin from outstanding hair for the reception of hair to be set on the skin.
67. In a fur pointing machine, a receptacle adapted to retain hair in parallel relation therein, a suction member having an adjustable suction slit therein, means for reciprocating the suction member into and out of the receptacle to dispose hair at and substantially to close the slit, said member being of less length than the receptacle whereby the hair projects beyond the member, openable gripping fingers, mechanism for opening said fingers on opposite sides of the hair held by the suction member, a spring adapted to close the fingers after their release by said mechanism, and means including a revolvable shaft for intermittently rotating the closed gripping fingers as a unit to advance the hair.
68. In a fur pointing machine, an adjustable suction member adapted to withdraw hair from a receptacle, and to retain full control of and to move said hair into a predetermined position, a turret, means for intermittently rotating said turret, a plurality of spaced pairs of normally closed gripping fingers on said turret, means for opening one set of said fingers at a time for arranging said fingers on opposite sides of the hair held by the suction member and for closing said fingers after the fingers have been so arranged; to grip the hair, a gum applicator adapted to be arranged in the path of the hair gripped by the fingers and adapted to gum the hair, and means for again opening said fingers for releasing the gummed hair for further advance thereof.
69. In a fur pointing machine, a container adapted to receive straight and parallel hair in a pile, a suction member adapted to reciprocate into and out of the container to withdraw hair while maintaining said hair straight, gripping fingers adapted to grip the hair retained by the suction member, means for rotating said gripping fingers as a unit, and means for gumming the hair.
70. In a fur pointing machine, a container adapted to receive straight and parallel hair in a pile, a suction member comprising a hollow block having an opening therein, a movable slide on the block adjacent said opening, and means for securing said slide in adjusted position to expose a predetermined amount of said opening communicating with the interior of the block, and means for reciprocating the suction member into and out of the container to withdraw hair arranged at said opening during the maintenance of

suction in said member, while maintaining said hair straight.

71. In a fur pointing machine, a revolute turret having a plurality of arms thereon, a stationary hair gripping finger on each of the arms, a movable hair gripping finger hinged to the stationary finger, and spring-pressed into engagement therewith, a cam adapted to engage and to move the movable finger relatively to the stationary finger to open the same for the reception and the release of hair at predetermined intervals, a box adapted to hold gum and to apply gum to the hair, and a pair of openable setting fingers in the path of the gummed hair and adapted to cooperate with a pair of gripping fingers to remove the gummed hair therefrom, said setting fingers being pivotally mounted for oscillatory movement.

72. In a fur pointing machine, a revolute turret having a plurality of arms thereon, a stationary hair gripping finger on each of the arms, a movable hair gripping finger hinged to the stationary finger, and spring-pressed into engagement therewith, and a cam adapted to engage and to move the movable finger relatively to the stationary finger to open the same for the reception and the release of hair at predetermined intervals.

73. In a fur pointing machine, a revolute turret having a plurality of arms thereon, a stationary hair gripping finger on each of the arms, and a movable hair gripping finger hinged to the stationary finger, and spring-pressed into engagement therewith.

74. In a fur pointing machine, a receptacle for substantially loose, parallel, substantially straight hair all lying through the length thereof in the same direction, a suction member adapted to engage and remove hair along a predetermined path from the receptacle and to position the hair for being gripped and advanced, gripping fingers adapted to grip the hair held by the suction member, means for rotating the fingers for advancing the hair toward the setting position on a fur skin, and means for gumming the hair.

75. In a machine for pointing furs, a hair receptacle having an opening therein, a suction picker adapted to reciprocate through the opening into and out of the receptacle, hair grippers adapted to be moved to grip the hair held by the picker and movable past the picker, separable setting members arranged beyond the path of the grippers but in the path of the hair held by the grippers, and a cam adapted to open said setting members at the setting position to release the hair.

76. In a fur pointing machine, means for removing hair from a receptacle comprising a hollow block having an opening therein adapted to have suction applied thereto and having a second opening therein connecting with the first-mentioned opening, a slid-able

member, and means for adjustably securing the slidable member to the block with an edge thereof at the second opening, to determine the effective width of said second opening and thereby to determine the number of individual hairs needed to block the opening, whereby the number of individual hairs removed by said means is controlled.

77. The method of pointing fur, comprising providing a bundle of hair, all of substantially the same length and arranged in parallel relation, removing hair from the bundle, gumming the hair and moving it toward a fur skin, simultaneously removing other hair from the bundle while the previously removed hair is being gummed, insetting the gummed hair among the roots of the hair of a fur skin while the second-mentioned hair is being gummed, and while still other hair is being removed from the bundle, blowing upon the skin to part the hair thereof while the gummed hair is being set in the skin, and moving the skin slightly after the first-mentioned hair has been inserted therein and between the next succeeding hair-inserting operations.

78. The method of pointing fur skins, comprising removing hair from a bundle which has been previously arranged so that all the hairs are substantially parallel and of substantially the same length, moving the hair so removed toward a fur skin in which the hair is to be inserted, and while so moving the hair, applying gum thereto and at the same time, removing other hair from the bundle, and inserting the gummed hair among the roots of the hair of the skin while moving the other removed hair toward the skin and applying gum thereto, and repeating these operations while moving the skin between succeeding hair insetting operations.

79. The method of pointing fur skins, consisting of moving hair toward a fur skin, applying gum thereto, then continuing the movement of the hair with the gum thereon to the skin, and simultaneously blowing upon the skin to part the hair thereof while at the same time, moving other hair toward the skin and gumming it, the first gummed hair being inserted among the natural parted hair of the fur skin while the movement of the second gummed hair is continued toward the skin.

80. The method of pointing a fur skin comprising substantially simultaneously performing the following operations upon hair to be inserted into said skin, namely, removing hair from a bundle, moving a second set of hair previously removed from the bundle toward the skin, gumming a third set of hair, blowing upon the skin to part the natural hair thereof, and inserting a fourth set of hair previously removed from the bundle and gummed, as aforesaid, among the parted hair of the skin.

81. The method of pointing a fur skin, comprising substantially simultaneously performing the following operations, namely, removing a set of hair from a bundle, moving 5 a second set of hair previously removed from the bundle toward the skin and gumming the hair, blowing upon the skin to part the natural hair thereof, and inserting a third set of hair previously removed from the bundle 10 and gummed, as aforesaid, among the parted hair of the skin, and between the aforesaid operations moving the skin step by step transversely through a total desired distance, and then moving the skin a predetermined distance longitudinally thereof.
